ANTI-ROLLING DEVICE FOR SHIPS

Nicholas X. Stephanou, SS "Pholegandros," % Global Chartering Co., 29 Broadway, New York, N.Y. 10001
Filed May 20, 1966, Ser. No. 551,756
5 Claims. (Cl. 114—126)

This invention relates to submersible marine stabilizers, and more particularly to an anti-rolling device for ships.

It is therefore the main purpose of this invention to provide an anti-rolling device for ships which will operate smoothly to considerably reduce the rolling action of a ship without exerting any jerking or turning action on said ship.

Another object of this invention is to provide an anti-rolling device for ships adapted to move in accordance with the speed of a ship without weaving and without objectionable drag on said ship.

Another object of this invention is to provide an anti-rolling device for ships, each side of said ship being provided with at least one stabilizing unit connected to said ship by means of a suspension cable or a tow-line in such a manner that it may be conveniently extended outwardly from said ship or pulled into said ship.

Still another object of this invention is to provide an anti-rolling device for ships which is easy to manufacture, and installed within a ship, capable of making the ship more sea worthy, reduces repair and maintenance costs on a ship due to storms and high seas, and provides maximum utility to its users.

Other objects and advantages of this invention will become apparent from a consideration of the following detailed description taken in connection with the accompanying drawing, wherein a satisfactory embodiment of the invention is shown. However, it is to be understood that the invention is not limited to the details disclosed but includes all such variations and modifications as fall within the spirit of the invention and the scope of the appended claims.

In the drawing:

FIGURE 1 is a schematic diagram illustrating the geometrical principles involved in this invention.

FIGURE 2 is a front elevational view of a ship sailing a calm sea with the anti-rolling devices positioned outwardly.

FIGURE 3 is a side elevational view of a ship illustrating of how the stabilizing units are towed.

FIGURE 4 is a front elevational view of a ship in a rough sea, showing the stabilizing units in their operating condition.

FIGURE 5 is a sectional-elevational view showing storage capacity for the stabilizing units and winches.

FIGURE 6 is a sectional-elevational view of stabilizing pillar showing hydraulic control of its movable beam.

FIGURE 7 is a side elevational view taken along lines 7—7 of FIGURE 6.

FIGURE 8 is a perspective view of the stabilizing unit.

According to this invention, an anti-rolling device for ships 10 is used for stabilizing a ship 11. Starboard and port sides of the ship 11 are provided with winch units 12 and 13. A tow line 14 is secured to the winch unit 12 and is adapted to extend upwardly towards the pulley 18, which is rotatably secured on the movable beam 19 of a stabilizing pillar 16. Beam 19 is vertically positioned within pillar 16 by means of a hydraulic piston 20. The bottom portion of pillar 16 is suitably secured on the

2

port side of the ship. Tow line 14 extends through pulley 18 and its end portion 14' is suitably secured to the stabilizing unit 21. On the starboard side of ship 11 a winch unit 13 supports the tow line 15 and rotatably secures it to the pulley 18 of a stabilizing pillar 17. It should be noted that pillar 17 is of identical construction as pillar 16 thereby permitting the tow line 15 to outwardly extend and be secured to the stabilizing unit 21 at 15'.

Looking now at FIGURE 5 of the drawing, one will see that in order to prevent any of the stabilizing units to drag behind the ship or to sink too deep into the water an auxiliary tow line 22 having a loop 23 maintains the tow line 15 (or 14) in parallel with the hull of ship 11. Each stabilizing unit 21 is provided with a pair of heavy duty fins 22 and 23 which are coplanar to each other and may be positioned at a desired depth or distance by means of expandable or retractable tow line 15 (or 14). During the lifting process of one of said stabilizing units 21 into the ship 11, auxiliary tow line 22 may be also used for positioning said unit within the ship board. Auxiliary tow line 22 may be extended by means of pulley 24 and an auxiliary winch unit 25 (see FIGURE 5).

It will also be noted that the height of pillars 16 and 17 is adjustable in relation of the position of the center of gravity of a ship thereby causing both stabilizing units 21 to resist the ship's rolling due to swell.

What I now claim is:

1. An anti-rolling device for ships comprising, in combination, an upwardly extendable pillar having a movable beam secured to each side of a ship, a winch unit near said each pillar, a tow line secured to said winch unit, a pulley secured to the movable beam, said pulley adapted to provide means for carrying said tow line in accordance with the operation of said stabilizer unit, a stabilizer unit secured to the free end of said tow line, said stabilizer unit when positioned in the water at a pre-determined distance from said ship is adapted to reduce the rolling action of said ship when it is used in conjunction with said substantially identical stabilizer unit positioned off the opposite side of said ship, and an auxiliary tow line arrangement flexibly secured to said tow line for controlling the movements of said stabilizer unit.

2. The combination according to claim 1, and a hydraulic piston member movably secured within the lower portion of said pillar for providing vertical propulsion to said beam.

3. The combination according to claim 1, wherein said stabilizer unit is provided with a pair of heavy duty fin members co-planar to each other, and said fin members being provided with means for admitting said free end of said tow line therebetween.

4. The combination according to claim 1, wherein said auxiliary tow line is provided with a loop adapted to flexibly move said tow line, and an auxiliary winch unit within said ship for expanding said auxiliary tow line.

5. The combination according to claim 4, wherein an auxiliary pulley unit is provided within said ship for carrying said auxiliary tow line in accordance with the operations of said auxiliary winch unit.
